UNITED STATES PATENT OFFICE.

ROBERT E. FRONK AND CHARLES E. KERSEY, OF KEWANEE, ILLINOIS.

EARTH-DRILL.

1,287,280.

Specification of Letters Patent. Patented Dec. 10, 1918.

Application filed January 3, 1917. Serial No. 140,394.

To all whom it may concern:

Be it known that we, ROBERT E. FRONK and CHARLES E. KERSEY, citizens of the United States, residing at Kewanee, in the county of Henry and State of Illinois, have invented certain new and useful Improvements in Earth-Drills, of which the following is a specification.

This invention relates to an improvement 10 in earth drills and particularly to means for locking the points to the ends of drill rods, and to this end it consists in providing the lower end of the drill rod in addition to the tapered internal thread with a plurality of 15 slots arranged concentrically with the axis of the drill rod and having inclined bottoms and in connection with said slots to fit the drill point with a plurality of screws extending upwardly therethrough at an angle 20 and adapted to project from the point after the latter has been secured into place in the end of the drill rod, into said slots for the purpose of holding the point against rotation relatively to the drill rod.

With the above as the main object in view 25 the invention consists of the novel construction, combination and arrangement of parts hereinafter described, pointed out in the appended claims, and illustrated in the accompanying drawings, in which—

Figure 1 is a longitudinal central section through the lower end of the drill rod and a drill point connected thereto and locked against rotation,

Fig. 2 is a cross sectional view on the line 2—2 of Fig. 1,

Fig. 3 is an end view of the drill point.

In the drawing, 10 indicates the lower end of a drill rod which is of indefinite length, 40 said lower end being formed with an axial recess, the walls of which are tapered inwardly and threaded as shown at 12 to engage the similarly threaded truncated upper end 13 of the drill point 14. The bottom 15 of the recess 11 has formed therein two or more curved slots 16 that are made concentric with the axis of the drill rod 10 and separated from each other by radial walls 17. Each slot 16 has its bottom inclined and one end, formed by the flat face of a wall 17, perpendicular to the bottom 15 of the tapered and threaded recess 11. From this end the bottom of the slot inclines outwardly, its other end terminating at the 55 outer end of another wall 17 flush with the

bottom 15 of the recess 11. These several slots form a concentric series of locking notches each having an end perpendicular and a bottom inclined to the bottom of the recess.

The drill point 14 just below the threaded portion 13 is preferably of the same diameter as the drill rod 10 but said drill point lower down tapers inwardly at 19 to the point proper 20.

Extending upwardly through the drill point 14 from the tapered portion 19 through the upper end of the threaded portion 13 are a number of long screws 21, the upper ends of said screws inclining toward the axis of the drill point and projecting at their upper ends into the notches 16 in the drill rod 10, the ends of these screws, which are shown equal in number to the number of notches 16, bear upon the inclined bottoms 75 of said notches or against the straight sides 18 of the walls 17 and lock the drill point against rotation. These screws 21 have heads 22 on their lower ends by means of which they may be backed out of the notches 80 16 when the drill point is to be removed from the rod 10 and advanced to their limit of movement so that their points will enter and engage in the slots 16. The heads 22 of these bolts fit in recesses 23 formed in the 85 tapered portion 19 of the drill point and are thus out of the way of the point when operating as a drill. Preferably two screws only are used placed diametrically on opposite sides of the axis of the drill point. 90 These two screws in connection with three notches in the drill rod 10 will enable at least one of said screws to always engage one of the notches and thereby prevent rotation of the drill point.

What we claim is:

1. In a device of the class described, a drill rod, a drill point threaded at one end into a recess in the end of the drill rod, and a screw threaded into said point in a longitudinal direction and converging toward the axis of the drill point to be projected by rotation from the threaded end of said point into one of a series of curved concentrically aligned slots in the bottom of said recess for locking the point in any position against backward rotation.

2. In a device of the class described, a drill rod having a threaded recess in one end, a drill point provided with a threaded

projection engaging said recess, a plurality of alined arcuate slots concentrically disposed in the bottom of said recess and having bottoms inclined at an angle to the bottom of the recess, and a bolt threaded longitudinally through the drill point from the exterior and converging toward the common axis of the drill rod and point to be projected by rotation from the end of the 10 threaded projection of said point for engaging one of said slots to lock the point to the drill rod in any relative position of rotation and prevent backward movement of the drill point.

15 3. In a device of the class described, a drill rod having a threaded recess in its lower end and a plurality of alined curved slots concentrically arranged about the axis

of said rod at the bottom of said recess, each slot having a bottom inclined at an angle 20 to the bottom of the recess, a drill point having a threaded extension on one end engageable with the threaded recess in the drill rod, and a plurality of bolts threaded longitudinally of said drill point and converging 25 inwardly to be projected by rotation from the end of said extension and engage the bottoms of said slots for holding said point in any position from backward rotation.

In testimony whereof we affix our signatures in presence of two witnesses.

ROBERT E. FRONK.

CHARLES E. KERSEY.
